DESIGN FOR A TEXTILE FABRIC

William A. Landry, White Plains, N. Y., assignor to Deering Milliken & Co., Incorporated, Manhattan, N. Y.

Application November 8, 1935, Serial No. 59,439

Term of patent 3½ years

To whom it may concern:

Be it known that I, William A. Landry, a citizen of the United States of America, residing in the city of White Plains, Westchester County,
State of New York, have invented a new, original,
and ornamental Design for a Textile Fabric, of which the following is a specification, reference being had to the accompanying drawing, forming part thereof.

The figure is a plan view of a textile fabric,
showing my new design.

I claim:

The ornamental design for a textile fabric substantially as shown.
